UNITED STATES PATENT OFFICE.

JOHN P. SCHNELLER, OF CATASAUQUA, PENNSYLVANIA.

HEAT-RADIATOR FOR SMOKE-PIPES.

SPECIFICATION forming part of Letters Patent No. 709,051, dated September 16, 1902.

Application filed March 20, 1902. Serial No. 99,111. (No model.)

To all whom it may concern:

Be it known that I, JOHN P. SCHNELLER, a citizen of the United States, residing in Cata-
saqua, county of Lehigh, State of Pennsyl-
5 vania, have invented certain new and useful
Improvements in Heat-Radiators for Smoke-
Pipes, of which the following is a specification.

My invention relates to an improved radi-
10 ator or drum for use in connection with a stove-
pipe to utilize a portion of the heat in the
products of combustion which is ordinarily
wasted.

15 My main objects are to provide a maximum
of effective heating-surface, while main-
taining a constant upward movement of the gases
to provide for conveniently connecting and
supporting the radiator.

20 The invention is fully described in connec-
tion with the accompanying drawings, and the
novel features are specifically pointed out in
the claims.

25 Figure 1 is a sectional front elevation of a
radiator embodying my improvements in pre-
ferred form. Fig. 2 illustrates a slight modi-
fication in the flue construction.

A and B represent similar bottom and top
radiator-sections, reversely arranged and con-
nected by one or more rows of vertical flues
30 C C, secured to the opposing flat walls a and
b, respectively, of the horizontal sections A
and B. The outer walls a' and b' of these
sections are outwardly arched and are pro-
vided midway of their length with smoke-pipe
35 connections D and D', which form, respec-
tively, an inlet and an outlet to and from the
radiator for the products of combustion.
These connections thus communicate with
the sections at the point of their greatest
40 height and equidistant from the end flues of
the row or rows of flues connecting them, and
the arched walls a' and b' both incline up-
wardly, so as to guide the gases in that direc-
tion. In order to distribute the latter equally
45 to the whole series of flues, I provide arched
deflector-plates E and E', respectively, in the
radiator-sections A and B, each arranged with
its concaved side opposite the inlet D and
outlet D', respectively, and having its oppo-
50 site ends inclined toward the arched wall a'
or b', but terminated at some distance there-
from, so as to prevent direct passage of the
heated gases to and from the more centrally

located flues, compelling them to move later-
ally toward the end flues, the inflowing gases
thus being divided, so that substantially equal 55
portions will rise through each of the series of
flues, and the outflow through the more cen-
tral flows being similarly diverted in the top
section, so as to cause the draft to pull equally
upon the end flues. 60

In order to more fully utilize the heat of
the gases and maintain a substantially uni-
form degree of heat in all portions of the ra-
diator, I preferably make the flues C of dou-
65 ble-conical form, with an enlarged cylindrical
portion C' midway of their height, and within
each flue I provide one or more partition-
plates c c, having reduced openings c' there-
through, the purpose of which is to insure the
70 storing or backing up of a body of the heated
gases in each of the different compartments
into which the flue is thus divided, thereby
insuring the more complete heating of the
walls of the flues. In order to further in-
75 crease the radiating-surface of the flues, they
may be made of corrugated or fluted sheet
metal, as indicated in Fig. 2, and the parti-
tion-plates c instead of being provided with
the central opening c' may be made, as indi-
80 cated in the latter figure, with opposite side
openings c² c² and with the plates inclined; as
shown, the effect being similar to that already
described.

To provide for more conveniently connect-
ing the radiator and supporting the same 85
when applied to a smoke-pipe leading through
the floor of the room in which it is located, I
provide hinged supports F F near opposite
ends of the lower section A, adapted to ad-
90 just themselves to the floor-line when the con-
nection D is attached to the smoke-pipe, thus
providing for slight variations in the height
of the radiator above the floor, to which lat-
ter the looped ends of the supports are fas-
tened after proper adjustment. 95

What I claim is—

1. A heat-radiator comprising top and bot-
tom sections connected by one or more rows
of vertical flues secured to the opposing flat
wall thereof, the lower and upper walls of said 100
sections being outwardly arched and having
inlet and outlet connections respectively lo-
cated midway of their length, and oppositely-
arched deflector-plates in said sections cov-

ering said openings and forming reduced side passage-ways thereto, whereby the draft through the connecting-flues is equalized substantially as set forth.

5. 2. The combination with the lower and upper radiator-sections of connecting double-conical flues having their reduced opposite ends connected to said lower and upper sections respectively and provided with partition-plates in the enlarged portions between the sections, said plates being formed with reduced passage-ways substantially as and for the purpose set forth.

10. 3. A heat-radiator comprising similar re-
15 versely-arranged top and bottom horizontal sections having opposing flat walls, and out-

wardly-arched outer walls with central openings, oppositely-arched deflector-plates in said sections covering said openings and forming reduced side passage-ways thereto, vertical double-conical flues having their reduced opposite ends connected to said opposing flat plates, and partition-plates in the enlarged portions of said flues having reduced openings therethrough substantially as and for the 20 purpose set forth.

In testimony whereof I affix my signature in the presence of two witnesses.

JOHN P. SCHNELLER.
